UNITED STATES PATENT OFFICE.

HUGH S. STUDDERT, OF SEATTLE, WASHINGTON.

STEAM-BOILER.

1,172,401.

Specification of Letters Patent. Patented Feb. 22, 1916.

Application filed September 29, 1914. Serial No. 864,035.

To all whom it may concern:

Be it known that I, HUGH S. STUDDERT, a citizen of the United States, residing at Seattle, in the county of King and State of 5 Washington, have invented certain new and useful Improvements in Steam-Boilers, of which the following is a specification.

My invention relates to steam boilers, and comprises the novel parts and combinations 10 of parts which will be hereinafter particularly defined by the claim.

The object of my invention is to provide a stronger and more efficient steam generator, especially for marine boilers, one which 15 will better stand the racking motion of a vessel, and one which can easily be cleaned and inspected.

Other objects will appear from a study of the specification and claim.

20 In the accompanying drawings, I have shown my invention in the form which is now preferred by me.

Figure 1 is a side elevation of my boiler, part of the casing being removed and part 25 being shown in section. Fig. 2 is an end elevation and partial section of my boiler.

In marine boilers, it is desirable that they should occupy very little space, be easy to clean, and yet strong enough to stand the 30 racking and quivering of the vessel. They must also be efficient and economical in operation. My boiler is designed to include all of these desirable features.

I provide a steam drum 1 which is of sufficient length to project through the ends 35 of the casing 7. This drum 1 is provided at the front end with the usual manhole 11 and is provided with main steam pipe 14. At front and rear, and entirely outside the casing 7, the drum is connected to down-flow pipes 2 and 3, in any suitable manner. As shown, the pipes 2 are connected by elbows 23 and horizontal pipes 24 with T-fitting 21 which, in turn, is secured to said drum. 40 The pipes 2 extend downwardly to mud-drums 4 positioned at each side of the boiler, and to which they are coupled by T-fittings 22. This forms an inverted U-shape connection between the steam drum 1 and respective mud-drums 4. The pipes 3, however, extend directly downward at each side from the drum 1, and are connected to mud-drums 4 by T-fittings 32. This forms an inverted V-shaped connection, and the

55 pipes 2 and 3 serve to support the drum 1, and hold it firmly in place against vertical and lateral strains.

The steam generator proper consists of a series of coils 5 connected with the mud-drums 4 by risers 53. These coils are each 60 constituted of a plurality of pipes which are disposed in inclined positions, as shown, to facilitate the circulation of the water therein and promote the flow of the generated steam to the drum 1, and are arranged in the fire-box to extend to within 65 a short distance of the center of the boiler. Instead of each individual coil being directly connected with the steam drum, a group of coils, preferably two, are joined at 70 51 by any suitable connection, and thence a single pipe 52 connects each pair of coils with the drum and at a distance above the water level therein. A doubling plate 13, so called, is advantageously provided to reinforce the drum where it is topped to receive the pipe connection 52 to compensate 75 for the borings in the drum shell and afford greater lengths of threads to engage 80 said connection.

To better distribute the furnace heat among the pipe coils, I provide baffle-plates 6 and 61 arranged in a peculiar manner. Two plates 6, one on each side of the boiler, extend horizontally just above the generating coils, from end to end of the boiler. These baffle-plates 6 are of widths to provide passages for the hot combustion gases between their inner sides and the steam-drum 1. A baffle-plate 61 is placed on a 90 plane below the plane of plates 6, and extends from the rear end of the casing to within a short distance from the front end thereof. This plate 61, however, does not touch the sides of the casing, but extends 95 outwardly from the center on both sides but part-way to the sides of the casing. More particularly, the baffles 6 and 61 contribute to direct the currents of heated gases, causing them to flow forwardly and laterally 100 from, and then against, the drum before escaping by stack outlet 75. By such device, a more effective heating of the coils and steam drum is attained than would otherwise obtain.

105 The casing 7 is provided with openings 71 at front and rear for the projection of the steam drum 1. This casing is also provided

with the usual openings, as the furnace doors 72, ash doors 73 and cleaning out openings 74.

I have left a space 76 between the coils 5, 5 the casing 7 and the steam-drum 1. This will allow a man to enter through one of the doors 74 to inspect or repair the boiler.

Inside the steam drum 1, and at a suitable distance above the discharge openings of 10 pipes 52, I place at each side a baffle-plate 12. This baffle-plate extends downwardly in front of the discharge openings, and is arranged so that the water and steam discharged from the generating coils 5 will impinge upon it, and be deflected downward, 15 as the pipes 52 are placed above the water level in the drum. The fluid thus impinging the plates will, in a measure, effect the separation of the steam from the accompanying water, the water discharged from 20 the coils falling into the body of water in the drum while the steam will mingle with that in the drum to be led off through pipe 14, and accordingly obviate the discharge 25 of saturated steam from the boiler.

If it is desired to remove one of the coils 5 for any reason, an operator may enter at 25 74 into space 76 to disconnect a coil at 55 or 54, and, by entering the door 72 into the 30 boiler furnace, the respective pipe 53 may be unscrewed for the removal of the coil. Where convenient, the side of the casing 7 may be detached and the coils taken out very 35 easily; otherwise a coil may have to be separated into parts which will pass through one of the casing doors. In this way the

coils may be quickly and easily removed for repairs when necessary.

Having described my invention, what I claim, is—

In a steam generator, in combination, a casing, a horizontal steam drum extending outside the casing at each end, horizontal mud-drums at each side of the generator and projecting from the casing at each end, 40 down-flow pipes at each end of, and entirely outside of, the generator connecting said steam-drum and said mud-drums, a series of generating coils connected in pairs immediately outside the steam drum and 45 connecting said mud-drums and said steam drum; said generating coils having one opening into the steam drum for each pair of coils, said openings being placed above the water level in said steam drum, a baffle- 50 plate in said steam drum immediately above the said openings and inclined downwardly, a baffle-plate at each side of the generator extending from end to end of the series of generating coils, and extending inward less 55 than half the width of the generator, and a baffle-plate placed below said first baffle- 60 plates, and extending from the rear forwardly less than the length of the generator and to the side less than the width of the 65 generator.

Signed at Seattle, Wash., this 1st day of September, 1914.

HUGH S. STUDDERT.
